GAS GENERATOR

Sulo Paavo Johannes Keinänen, Helsinki, Finland

Application December 20, 1947, Serial No. 792,875
In Sweden November 16, 1943Section 1, Public Law 690, August 8, 1946
Patent expires November 16, 1963

7 Claims. (Cl. 48—111)

1

The object of the present invention is to make it possible to use in gas generators, heating ovens and the like, extremely wet fuel, as for instance newly cut live wood or still wetter wood with a percentage of water of about 50%. This wood so far has simply been raw material for fuel and first after drying either in open air or in ovens at great expense has become ready for use.

Attempts have even earlier been made to construct gas generators, heating ovens and the like devices so as to make it possible to use raw wood in them as fuel, but these attempts have not led to desired results, because when heating raw wood so great quantities of distillates develop that the heat in the fire chamber is not sufficient to decompose them into hydrogen and oxygen. Moreover, the penetration of the distillates into the fire chamber reduces its temperature so greatly that in the case of gas generators it has not been possible to generate gas that would be fit for use.

According to the present invention the device in which extremely wet fuel is desired to be used, must be provided with a fuel container having a compartment that is kept as cold as possible and so placed that the heat radiating from the fire chamber cannot influence it, and in which compartment there is a chance for the steam and vapors developed to condense against the cold surfaces and/or against the fuel material. Secondly, the bottom of the fuel container must be constructed so that it prevents the steam that has condensed against the walls of the fuel container and/or upon the fuel material in the cold compartment from leaking into the fire chamber. In applying these principles to such a gas generator, heating oven or other like device where there is a fuel container placed on a higher level than the fire chamber, on the lower part of which container there is an orifice through which the fuel is led into the fire chamber, one proceeds in the manner that the fuel container is made sidewise larger than the said orifice and the bottom of this larger part in whole or part forms a space for collecting the distillates, which space is provided with an aperture to discharge the distillates from the fuel container.

The invention is more particularly described with reference to the accompanying drawing showing the lower part of a fuel container of a gas generator in central vertical section.

In the drawing 1 is a fire chamber of a gas generator, 2 the space wherein the fuel is pre-heated or the so-called pre-heating room, 3 is the fuel container, the lower part of which is

shown in the drawing. The pre-heating room 2 is surrounded by a chamber 4, through which the generated gas flows on its way to the exhaust pipe 5. When flowing the gas forms the wall 6 of the pre-heating room 2. The wall 6 slopes funnel-like onto the fire chamber 1 and is actually an inclined feeding chute which forms a part of the bottom of the fuel container. The rest of the bottom is marked with 7. Above the part 7 is placed a distillate grate 8. The horizontal distance between the upper edge of the inclined wall or feeding chute 6 of the pre-heating room 2 and the wall of the fuel container 3 is marked with *a*. The distance *a* must be considerable, preferably at least 5–10 cm., in order that the heat which develops partly in the fire chamber 1 and partly even in the lower part of the pre-heating room 2 may not heat the distillate grate, nor the bottom beneath it nor the fuel layer on the grate 8 too much, all of which must act as condensers for the steam and vapors developed. The distance *a* must be considerable also in order to obtain an insulating layer sufficient to prevent the heat developed by the generator from passing into the open air through the wall of the fuel container. The distillate grate 8 preferably slopes toward the upper part of the pre-heating room 2, in order to lead the fuel into the fire chamber. The bottom part 7 of the fuel container slopes outward, so that the distillates leaking through the distillate grate or along the walls be prevented from passing into the fire chamber. Along the bottom part 7 the distillates run to the farthest or the lowest and at the same time the coolest portion of the bottom, wherefrom they pass into the distillate container 9.

The gas generator operates as follows: The heat developed in the fire chamber and the generated gases warm the fuel in the pre-heating room 2, so that the moisture evaporates from the fuel and condenses on the walls and/or on the fuel layer supported by the distillate grate 8. The distillates condense partially also against the fuel in the space above the pre-heating room. The distillates, condense partially also against temperature evaporate anew, and partly pass upward to condense again and partly enter the fire chamber by the influence of the suction of the engine. The steam and vapors, which condense and penetrate into the fuel layers upon the distillate grate 8 are absorbed by the fuel material and run down in the form of distillates when the fuel has become saturated. The temperature of this layer of fuel is low, so that the

distillates flow through this layer and the distillate grate 8 onto the bottom part 7 which leads them into the container 9. In such a way a part of the entire amount of moisture leaves the generator and a part flows into the fire chamber, decomposing into hydrogen and oxygen, thus accelerating the combustion and raising the heat value of the generated gas. Inasmuch as fuel like wood contains considerably more water than what the temperature in the fire chamber can decompose into hydrogen and oxygen, it is important that the excessive part of the water be prevented from entering the fire chamber of the generator. How much water in each case is to be removed depends of course on the humidity of the fuel used.

From the foregoing it is clear that the fuel layer supported by the distillate grate 8 operates as a condenser of the steam and other vapors, as an accumulator of moisture, as a regulator of the amount of steam and vapors entering the fire chamber and as a discharger of excess water. By dimensioning the fuel container of the generator in a suitable way, one can arrange that into the fire chamber continually flows just the amount of steam and vapors that is most advantageous for the formation of hydrogen, no matter how wet the fuel used is. This gives the great advantage that has not been attained by using gas generators constructed according to the principles so far considered as being the only right ones. The experiments made have shown that the generators according to this invention produce excellent gas, even if the humidity of the fuel is very great, as is the case in newly cut live wood, which as such can be used as fuel in the gas generator according to this invention.

The invention offers in addition the advantage that the surfaces of the gas coolers and purifiers need not be so large as in the generators thus far known, because the steam and vapors condense already in the fuel container and not alone in the coolers and purifiers.

The form of construction shown above is naturally intended only to illustrate the spirit of the invention. The forms of construction can vary considerably within the frame of this invention. Thus, in so far as a distillate grate is used, it need not be just in the position shown in the drawing: the main idea being that it permits only the distillates to pass through, but not the fuel.

The bottom part of the fuel container collecting the distillates is preferably placed entirely or partially on a lower level than the upper edge of the orifice leading the fuel into the fire chamber. The same object, namely the preventing of the distillates from running into the fire chamber from the distillate collecting space, can be attained also by providing the bottom of the fuel container or the upper end of the orifice leading the fuel into the fire chamber with a collar or the like.

Having now described my invention, what I claim is:

1. A gas generator or heating stove adapted for burning wood or other damp fuel and having a space for collecting distillates derived from said fuel, said gas generator comprising a fire chamber wherein the fuel is to be burned; air inlet means disposed about and above the fire chamber to supply air downwardly through the latter chamber; a fuel supply chamber located above the fire chamber and the air inlet means and in open communication therewith, said fuel supply

chamber comprising at least one inclined fuel supporting section extending and diverging outwardly from the top of the fire chamber and adapted to be heated by the gases escaping from said fire chamber, and said inclined fuel supporting section being adapted to both support a portion of the fuel bed and also to allow distillates to pass said inclined fuel supporting section to said space for collecting said distillates beyond said inclined fuel supporting section.

2. A gas generator or heating stove adapted for burning wood or other damp fuel and having a space for collecting distillates derived from said fuel, said gas generator comprising a fire chamber wherein the fuel is to be burned; air inlet means disposed about and above the fire chamber to supply air downwardly through the latter chamber; a fuel supply chamber located above the fire chamber and the air inlet means and in open communication therewith, said fuel supply chamber comprising an inclined feeding chute extending and diverging outwardly from the top of the fire chamber and adapted to be heated by the gases escaping from said fire chamber; and a grate section extending outwardly and upwardly from the outer edge of the inclined feeding chute, the latter and said grate section being adapted to both support a portion of the fuel bed and also to allow distillates to pass said inclined feeding chute and through said grate section to said space for collecting said distillates beyond said inclined feeding chute and grate section.

3. A gas generator or heating stove adapted for burning wood or other damp fuel and having a space for collecting distillates derived from said fuel, said gas generator comprising a fire chamber wherein the fuel is to be burned; air inlet means disposed about and above the fire chamber to supply air downwardly through the latter chamber; a fuel supply chamber located above the fire chamber and the air inlet means and in open communication therewith, said fuel supply chamber comprising an inclined feeding chute slanting upwardly and outwardly from the top of the fire chamber and adapted to be heated by the gases escaping from said fire chamber; and a grate section extending outwardly and upwardly from the outer edge of the inclined feeding chute, the latter and said grate section being adapted to both support a portion of the fuel bed and also to allow distillates to pass over said inclined feeding chute and through said grate section to said space for collecting said distillates beyond said inclined feeding chute and grate section.

4. A gas generator or heating stove adapted for burning wood or other damp fuel and having a space for collecting distillates derived from said fuel, said gas generator comprising a fire chamber wherein the fuel is to be burned; air inlet means disposed about and above the fire chamber to supply air downwardly through the latter chamber; a fuel supply chamber located above the fire chamber and the air inlet means and in open communication therewith, said fuel supply chamber comprising an inclined annular feeding chute slanting upwardly and outwardly from the top of the fire chamber and adapted to be heated by the gases escaping from said fire chamber; and an annular grate section extending outwardly and upwardly from the outer edge of the inclined annular feeding chute, the latter and said annular grate section being adapted to both support a portion of the fuel

bed and also to allow distillates to pass said inclined annular feeding chute and through said annular grate sections to said space for collecting said distillates beyond said inclined annular feeding chute and annular grate section.

5. A gas generator or heating stove, adapted for burning wood or other damp fuel, comprising a fire chamber wherein the fuel is to be burned, an upwardly extending bounding wall at least partly defining air inlet means disposed about and above the fire chamber to supply air downwardly through the latter chamber; a fuel supply chamber located above the fire chamber and the air inlet means and in open communication therewith, said fuel supply chamber comprising at least one inclined fuel-supporting section or feeding chute extending upwardly and outwardly from the top of the fire chamber to a predetermined distance from said bounding wall and adapted to be heated by the gases escaping from said fire chamber; a downwardly and outwardly sloping wall extending from the outer upper edge of the inclined fuel-supporting section or feeding chute to the lower portion of said bounding wall for receiving and guiding distillates away from said fuel-supporting section or feeding chute; and means for collecting the distillates from the downwardly and outwardly sloping wall beyond said fuel-supporting section or feeding chute, the latter being adapted both to support at least a portion of the fuel bed and also to allow distillates to pass said fuel-supporting section or feeding chute to said downwardly and outwardly sloping wall within said bounding wall.

6. A gas generator or heating stove, adapted for burning wood or other damp fuel, comprising a fire chamber wherein the fuel is to be burned, an upwardly extending bounding wall at least partly defining air inlet means disposed about and above the fire chamber to supply air downwardly through the latter chamber; a fuel supply chamber located above the fire chamber and the air inlet means and in open communication therewith, said fuel supply chamber comprising an inclined feeding chute slanting upwardly and outwardly from the top of the fire chamber to a predetermined distance from said bounding wall and adapted to be heated by the gases escaping from said fire chamber; a downwardly and outwardly sloping wall extending from the outer upper edge of the inclined feeding chute to the lower portion of said bounding wall for receiving and guiding distillates away from said inclined feeding chute; a second grate section extending outwardly and upwardly from the outer upper

5 edge of said inclined feeding chute above the downwardly and outwardly sloping wall to said bounding wall; and means for collecting the distillates from said outwardly and downwardly sloping wall beyond said inclined feeding chute and grate section, the latter being adapted both to support a portion of the fuel bed and also to allow the distillates to pass said inclined feeding chute and through said grate section to said downwardly and outwardly sloping wall within said bounding wall.

10 7. A gas generator or heating stove, adapted for burning wood or other damp fuel, comprising a fire chamber wherein the fuel is to be burned, an upwardly extending annular bounding wall at least partly defining air inlet means disposed about and above the fire chamber to supply air downwardly through the latter chamber; a fuel supply chamber located above the fire chamber and the air inlet means and in open communication therewith, said fuel supply chamber comprising an inclined annular feeding chute slanting upwardly and outwardly from the top of the fire chamber to a predetermined distance from 15 said annular bounding wall and adapted to be heated by the gases escaping from said fire chamber; a downwardly and outwardly annular sloping wall extending from the outer upper edge of the inclined annular feeding chute to the lower portion of said annular bounding wall for receiving and guiding distillates away from said inclined annular feeding chute; an annular grate section extending outwardly and upwardly from the outer upper edge of said inclined annular 20 feeding chute above the downwardly and outwardly annular sloping wall to said annular bounding wall; and means for collecting the distillates from said outwardly and downwardly annular sloping wall beyond said inclined annular feeding chute and annular grate section, the latter being adapted both to support a portion of the fuel bed and also to allow the distillates to pass said inclined annular feeding chute and through said annular grate section to said downwardly and outwardly annular sloping wall within 25 said annular bounding wall.
